UNITED STATES PATENT OFFICE.

JOSHUA B. HALE, OF PROVIDENCE, RHODE ISLAND, ASSIGNOR TO TEXTILE ENGINEERING COMPANY, OF PROVIDENCE, RHODE ISLAND, A CORPORATION OF RHODE ISLAND.

BRAIDING-MACHINE CARRIER.

Application filed November 2, 1921. Serial No. 512,318.

To all whom it may concern:

Be it known that I, JOSHUA B. HALE, a citizen of the United States, and a resident of Providence, in the county of Providence and State of Rhode Island, have invented an Improvement in Braiding-Machine Carriers, of which the following description, in connection with the accompanying drawings, is a specification, like characters on 10 the drawings representing like parts.

This invention relates to braiding machine carriers and particularly to braiding machine carriers having resilient bodies.

In order that the principle of the invention may be readily understood, I have disclosed a single embodiment of my invention, wherein—

Fig. 1 is a top plan view;

Fig. 2 is a side elevation;

20 Fig. 3 is a vertical section on the line 3—3 of Fig. 2; and

Fig. 4 is a plan view with parts broken away, showing so much of a braiding machine as is necessary to illustrate the functioning of my improved braiding carrier 25 and the advantages thereof in operation.

Braiding machine carriers or members, sometimes termed trackers, which support the yarn supply and travel in circuitous or 30 other raceways, are of various structures. In my co-pending application Serial No. 356,363, I have represented a carrier of approved form and to which my present invention may be applied though obviously 35 this invention is not limited in its application thereto but is of broad application.

A braiding carrier is provided with a body portion whereon the yarn supply is carried and a bearing or guiding surface 40 which cooperates with other parts of the braiding machine, as for example the rotating quoits and the fixed portions of the body structure.

Heretofore, so far as I am aware, the bearing or guiding portions of carriers or 45 trackers have been formed as a solid mass of metal shaped to fit its path.

It is obvious that owing to the high speed at which these carriers travel they impact 50 or strike with great force upon the unresisting walls forming the raceways and particularly at those portions of the raceways where the direction of the carriers is changed.

An important object of my invention is to provide a resilient support or guide member for the carrier or tracker which, when it strikes a portion of the wall of the raceway necessitating or compelling a change in direction of the carrier, will absorb the shock of impact and thus prevent the jarring of 60 the parts as well as largely to eliminate noise or chatter.

While my invention may be carried out in many ways, I have herein represented at 1 in the several figures a part of the upper portion of the carrier and whereon the yarn is carried. The lower portion of the carrier is herein indicated as a solid enlargement 2 of general elliptical shape but having flattened ends. The size or dimensions of the 65 enlargement 2 should be such as to leave space therebetween and the walls of the raceway and for the accommodation of the resilient portion of a carrier constituting 70 an important feature of my invention. As most clearly shown in Figs. 1 and 2, I provide at opposite faces of the enlargement 2 the two curved plates 3, 4 of some suitable sheet material, such, for example, as case hardened steel of desirably a thickness of 75 .04 of an inch. Obviously my invention is not limited to this material or to this proportion of parts. The said curved plates 3, 4 may be secured to the enlargement in any suitable manner, as, for example, by 80 bolts 5, 6 passing through said enlargement and through the plates 3, 4, said bolts being provided with heads 7, 7 which are desirably countersunk as indicated so as to provide a smooth outer surface.

Desirably the ends of the plates 3, 4 are not connected but are slightly spaced as indicated at 8, 9 so that they may yield relatively to each other in the travel of the carriers in the raceways and when the impact 95 to which I have referred occurs.

The bolts 6 may be positioned at any suitable point but desirably they are relatively close to the body portion 1 and are so positioned that the inner walls of the plates 3 and 4 are normally slightly spaced from the outer surface of the enlargement 2 as clearly indicated in Fig. 1 at 10. This permits the yielding of the walls of the bearing or guiding surface of the carriers. 100 In the preferred form of my invention, the

plates 3 and 4 constitute a resilient casing or sheathing.

So far as I am aware, I am the first to provide a carrier with an inner preferably rigid body or shank having a yielding or resilient bearing surface.

Obviously other formations may be employed within the scope and purpose of my invention but in that form herein disclosed 10 the resilient members or plates 3, 4 may be taken off from the shank or body portion of the carrier and be replaced if worn at low cost compared with the replacement of the entire carrier.

Viewing Fig. 2, it will be evident that the bearing or guiding portion of the carrier is composed of an upper portion *a* and a lower portion *b* united by a web *c*, the parts *a*, *b* and *c* of each plate 3, 4 being an integral 15 structure. Thus the members *a* *b* are not strictly bifurcated but are connected at their extremities by the web *c*, thereby more accurately locating and positioning the parts of the said plates and in such a manner as 20 to give greater strength and endurance. Obviously my invention is not limited to a bifurcated structure of braiding carrier bearing or guiding member which is herein merely shown for purposes of illustration 25 since my invention is of broad application and is intended to be used in any relation wherein a resilient or yielding bearing or guiding portion of a braiding carrier may be employed. In those cases where there 30 are provided upper and lower portions *a*, *b* connected by a web *c*, the quoits should be provided with suitable cut-out formations permitting the passage of such portions of 35 the carrier. In Fig. 4 where I have represented at 11 a portion of the quoits, it will be observed that I have provided cut-out formations 12 for the purpose set forth. In Fig. 4 I have indicated sufficient of the 40 structure of a braiding machine to make clear certain advantages of my invention. Therein I have indicated four braiding carriers or parts thereof. It will be clearly 45 evident that each of said carriers together with its load and its over-works must be reversed in direction because of the impingement of said carriers against a wall of the raceway in which it is traveling. For example, the carrier A moving from the point 50 A' in the direction of the arrow adjacent thereto and in a general clockwise direction will impact against the mass A² of the body structure. This impact is of very considerable force and especially where the parts 55 are rotating at high speed and the load of thread is large. By making the guiding and bearing portion of the carrier yielding and resilient as herein set forth, I accomplish numerous important results, among 60 which are the decrease in the noise, the loss 65 of wear, the absorption of shock and a sub-

stantial increase in speed. By employing a yielding or resilient portion I therefore not only overcome certain objections which have heretofore existed but by avoiding said objections I am enabled to increase the speed 70 of the carriers.

It will be observed that the resilient plates or members 3, 4 are on substantially the same radius as that of the wall of the raceway, whereas the solid enlargement 2 is of a 75 less radius, thus permitting the yielding of said plates or members 3, 4.

Having thus described one illustrative embodiment of my invention, I desire it to be understood that although specific terms are employed, they are used in a generic and descriptive sense and not for purposes of limitation, the scope of the invention being set forth in the following claims:

1. A braiding machine carrier having that part thereof which is adapted to run in the raceway, composed of a solid member having a resilient bearing surface located in part at least upon the ends of said member and there serving as a resilient member and also preventing contact of said rigid member with the walls of the raceway.

2. A braiding machine carrier having that part thereof which is adapted to run in the raceway, composed of a rigid body portion with resilient opposite lateral bearing surfaces rigidly attached to said body portion at the opposite sides thereof.

3. A braiding machine carrier having that part thereof which is adapted to run in the raceway, composed of a rigid bearing portion having a surrounding resilient member.

4. A braiding machine carrier having that part thereof which is adapted to run in the raceway composed of a rigid bearing portion having as side walls opposite bearing plates adapted to impact against the walls of the raceway and to absorb shock.

5. A braiding machine carrier having that part thereof which is adapted to run in the raceway composed of a rigid member, the lateral faces of which are of a less radius than the walls of the raceway, said rigid member having outer resilient members of substantially the same radius as the said walls of the raceway.

6. A braiding machine carrier having that part thereof which is adapted to run in the raceway composed of a solid bearing portion and a resilient casing attached thereto but spaced therefrom at its ends.

7. A braiding machine carrier having that part thereof which is adapted to run in the raceway composed of a solid bearing portion and a resilient casing attached thereto only intermediate its ends, whereby the latter yield and absorb shock.

8. A braiding machine carrier having a bifurcated bearing portion joined at its extremities, in combination with a rotatable

quoit having an extending flange itself having a carrier-driving-recess, and adjacent recesses to permit clearance for said joining portions of the bifurcation.

5 9. A braiding machine carrier having that part thereof which is adapted to run in the raceway composed of a rigid bearing portion and a resilient casing attached thereto only intermediate its ends and extending 10 beyond the ends of the solid bearing portion, whereby said casing absorbs shock.

10. A braiding machine carrier having that part thereof which is adapted to run in the raceway, composed of a body portion 15 and a resilient casing or sheathing adapted to absorb shock.

11. A braiding machine carrier having that part thereof that is adapted to run in the raceway composed of a rigid portion 20 adapted to support the yarn supply and yarn controlling mechanism, and a resilient member which alone is adapted to contact with the walls of the raceway, thereby to absorb

shock, said resilient member preventing contact of said rigid portion with the walls of 25 the raceway.

12. A braiding machine carrier having that part thereof that is adapted to run in the raceway, composed of a rigid portion adapted to support the yarn supply and 30 yarn controlling mechanism, and a resilient casing member for said rigid portion, and which casing member alone is adapted to contact with the walls of the casing, thereby to absorb shock. 35

13. A braiding machine carrier having that part thereof which is adapted to run in the raceway composed of an inner member, a lateral face whereof is of less radius than the walls of the raceway, said inner 40 member having an outer resilient member of substantially the same radius as the said walls of the raceway.

In testimony whereof, I have signed my name to this specification.

JOSHUA B. HALE.
